MOP ATTACHMENT

Anna Tringa, Oakville, Conn.

Application March 16, 1936, Serial No. 68,992

6 Claims. (Cl. 15—246)

This invention relates to mops, and more particularly to an attachment for the common wet mop frame which will enable it to be also used as a "dry" mop.

5 One object of the present invention is to provide a rectangular bumper pad of soft cushioning material which may be detachably assembled upon a metal mop frame, and is adapted to project beyond the periphery of said frame.

10 Another object is to provide a protective bumper pad of the above nature which is adapted to be readily assembled to a standard "wet" mop frame, and will be securely clamped in position by the usual clamping lever of said frame.

15 A still further object is to provide a mop attachment of the above type which will be simple in construction, inexpensive to manufacture, and very efficient and durable in use.

With these and other objects in view, there 20 has been illustrated on the accompanying drawing one form in which this invention may be embodied in practice.

In the drawing:

Fig. 1 is a front view of a mop embodying 25 the features of this invention.

Fig. 2 is a side view of the same.

Fig. 3 is a top plan view of the cushion bumper pad.

Fig. 4 is a sectional view of said pad taken 30 on the line 4—4 of Fig. 3.

Fig. 5 is a sectional view of the same taken on the line 5—5 of Fig. 3.

The conventional types of wet mops now in general use cannot be efficiently and safely used 35 for dry cleaning in view of the danger of scratching or otherwise injuring the wall boards or furniture legs by the metal frame of the mop. By means of the present invention, a scratch preventing bumper for the conventional type of 40 mop frame has been devised whereby the above and other disadvantages are avoided.

The standard mop selected to illustrate the features of this invention comprises an elongated wooden handle 10, a mop frame 11 secured to the 45 end of the handle 10, a bumper pad 12, and a plurality of cloth strips 13. The clamping frame 11 includes a rectangular slidable wire bail 14 which may be drawn up toward a cross-bar 15 fixed to said handle 10, by a hand-operated 50 clamping toggle lever 16 for clamping the mop rags 13 therebetween, a coiled spring 17 being employed to securely press the cross-bar 15 upon the rags 13 located between said cross-bar and 55 the bail 14. The spring 17 acts between a han-

dle receiving hub 18 on the cross-bar 15 and one arm of the lever 16.

The lever 16 is slidable on the handle 10 and is also pivoted to the upper coil of the spring 17 by a loop 19. Sockets or eyes 20 are provided 5 in a pair of side ears 21 and 22 on said lever 16 to receive the ends 23 and 24, respectively, of the bail 14, whereby the bail will be held in rag-clamping position when the lever 16 is disposed in the "up" or full-line position of Fig. 2. 10 When, however, the lever 16 is swung into the dotted "down" position shown in Fig. 2, the bail 14 will be moved up away from the cross-bar 15 and the rags 13 will be released.

The cushion bumper pad 12 shown in detail 15 in Figs. 3, 4 and 5 is preferably made of soft resilient rubber or other material having similar physical characteristics, so as to serve as a protection against marring the wall boards or furniture when the mop is in use. The bumper 20 12 is adapted to lie with its plane at right-angles to the longitudinal plane of the bail 31, and is situated between the cross-bar 15 and the cloth strips held in the base of the bail 14. The cushion pad 12 extends slightly beyond the sides and 25 ends of said cross-bar and has a thin flat central yieldable section 25 provided along each of its longitudinal sides with a narrow reinforcing rib 26 which is connected with somewhat wider and thicker U-shaped end ribs 27. The thin ribs 30 26 extend only slightly above the upper and lower surfaces of the flat central web 25 of the cushion pad, while the thick ribs 27 are raised a greater amount above the upper surface of the 35 pad 12 so as to lie above all the metal parts of the mop frame 11.

The central flat web 25 of the cushion pad 12 is provided adjacent its ends with a pair of circular holes 28 and 29 within which the side bars 30 and 31 may be seated.

In order to permit the cushion pad 12 to be 40 readily assembled upon the mop frame, provision is made of a pair of oppositely inclined holes 32 and 33 extending from said sockets 28 and 29 to one side edge of said pad. By bending one 45 end of the cushion pad 12 outwardly at one of the holes 28 or 29, the pad may be readily assembled to one of the side bars 30 of the bail 14 by passing said bar through the adjacent slot 32 or 33 until it slips into the respective 50 hole 28 or 29. The other bar may then be assembled in a similar manner.

Operation

When it is desired to use the improved mop 55

either "wet" or "dry", the desired quantity of mopping fabric will first be placed between the bail 14 and the cushion pad 12, and clamped in place by means of the lever 16 and spring 17, 5 as shown in full lines in Figs. 1 and 2. The rubber cushion pad 12 will then prevent the metallic bail 14 and cross-bar 15 from scratching or otherwise injuring the walls, floor or furniture.

While there has been disclosed in this specification one form in which the invention may be embodied, it is to be understood that this form is shown for the purpose of illustration only, and that the invention is not to be limited to the specific disclosure but may be modified and 15 embodied in various other forms without departing from its spirit. In short, the invention includes all the modifications and embodiments coming within the scope of the following claims.

Having thus fully described the invention, what 20 is claimed as new and for which it is desired to secure Letters Patent, is:

1. A new article of manufacture comprising a scratch-preventing bumper pad for a mop, said pad being of soft resilient material having a comparatively thin elongated central body portion, 25 said body portion being provided with a pair of longitudinally spaced holes to receive the side members of a mop frame bail, said holes being connected by slots to the side of said pad to permit said pad to be readily assembled upon a standard mop frame bail, and a strengthening enlarged rib extending about the periphery of said body portion.

2. A new article of manufacture comprising a 35 flat elongated bumper pad for a mop, said pad being of soft cushioning resilient material having a comparatively thin body portion for snugly embracing the cross-bar and bail of a wet mop frame, and a strengthening enlarged rib extending 40 about the periphery of said body portion, the portions of said rib at each end of said pad being wider than the intermediate portions of said rib.

3. A new article of manufacture comprising a 45 flat elongated bumper pad for a mop, said pad being of soft cushioning resilient material having a comparatively thin body portion for snugly embracing the cross-bar and bail of a wet mop frame, and a strengthening enlarged rib extending about

the periphery of said body portion, the portions of said rib at each end of said pad being thicker and wider than the intermediate portions thereof.

4. In a device for use on a mop of the type 5 having an elongated handle, a cross-bar secured to said handle, a slideable bail, and means to force said bail upwardly to clamp the mopping elements between it and the cross-bar; an elongated bumper pad adapted to be disposed between said mopping elements and said cross-bar and extending along the length of said cross-bar and laterally beyond the peripheral edges of said cross-bar, said pad comprising a separate unit unattached to said cross-bar, said pad having means 10 extending below the bottom of said bail to prevent the latter from scratching the floor.

5. In a device for use on a mop of the type 15 having an elongated handle, a cross-bar secured to said handle, a slideable bail, and means to force said bail upwardly to clamp the mopping elements between it and the cross-bar; an elongated bumper pad adapted to be disposed between said mopping elements and said cross-bar and extending 20 along the length of said cross-bar and laterally beyond the peripheral edges of said cross-bar, said pad comprising a separate unit unattached to said cross-bar, said pad having means extending below the bottom of said bail to prevent the latter from scratching the floor and having 25 a pair of holes to receive the longitudinal side members of said mop frame bail.

6. In a device for use on a mop of the type 30 having an elongated handle, a cross-bar secured to said handle, a slideable bail, and means to force said bail upwardly to clamp the mopping elements between it and the cross-bar; an elongated bumper pad adapted to be disposed between said mopping elements and said cross-bar and extending 35 along the length of said cross-bar and laterally beyond the peripheral edges of said cross-bar, said pad comprising a separate unit unattached to said cross-bar, said pad having means extending 40 beyond the side edges of said bail to prevent the latter from scratching the walls and having 45 a pair of holes to receive the longitudinal side members of said mop frame bail.

ANNA TRINGA.
